UNITED STATES PATENT OFFICE.

HERBERT R. HYMAN, OF INDIANAPOLIS, INDIANA, AND TURNER B. MESSICK, OF TOLEDO, OHIO.

PROCESS OF SECURING DEPTH AND RELIEF FOR COMMERCIAL ADVERTISING.

1,339,892.

Specification of Letters Patent.

Patented May 11, 1920.

Application filed September 6, 1919. Serial No. 322,090.

To all whom it may concern:

Be it known that we, HERBERT R. HYMAN and TURNER B. MESSICK, citizens of the United States, and residents of Indianapolis and Toledo, counties of Marion and Lucas, respectively, and States of Indiana and Ohio, respectively, have invented a certain new and useful Process of Securing Depth and Relief for Commercial Advertising; and we do hereby declare that the following is a full, clear, and exact description thereof, reference being had to the accompanying drawings, in which like numerals refer to like parts.

15 This invention relates to a process of making or forming a reproduction or illustration of an article for sale adapted for use in display advertisements, particularly with reference to reproductions for magazines, 20 posters and the like wherein the matter is printed or lithographed.

The principal object of this process is to so form the illustration of the product whereby a natural depth of relief is obtained 25 so as to form natural shadows in the reproduction, which cannot be artificially produced. This is obtained by mounting a plurality of layers of thick cardboard together and cutting away certain portions of the 30 layers after the figure has been outlined thereon, so as to obtain an actual depth of relief in perspective.

An important feature of this invention is the method in which the layers of cardboard 35 are secured together, whereby the layers may be securely and permanently affixed to each other, and certain portions of the outer layers cut and peeled away leaving the exposed layers clean and free from any adhering material, the use of ordinary adhering material such as glue making the process impossible for the reason that it is difficult to remove from the surface after portions of the cardboard have been cut away.

45 Referring to the drawings, which are made a part of this application, Figure 1 is a front elevation showing the cardboard with a figure outlined thereon. Fig. 2 is a section taken on the line 2-2 of Fig. 1. 50 Fig. 3 is a section taken on the line 3-3 of Fig. 1.

In the drawings there is shown a background or mounting 10 consisting of a piece of bright colored silk velvet which is mounted 55 on a panel of suitable size, folded around

and pasted securely on the back thereof. The panel 10 may be shaded appropriately and artistically by the use of Maratta water color and any suitable design 11 painted thereon, the shades of the figure being produced by water color as above indicated.

For producing the figure 12 to be mounted thereon, a plurality of sheets or layers of thick cardboard are secured together so as to form a laminated sheet or board 13, which 60 preferably consists of four layers of three-ply-Strathmore bristol board. The layers of cardboard are secured together by means of rubber cement which forms an adhesive element which will permanently and securely 65 affix the layers together, or which may be easily and readily removed when portions of the layers are cut away by simply peeling off the film of rubber cement so as to leave the exposed surfaces of cardboard clean and 70 dry. A photograph or outline of the object to be illustrated is then mounted upon the outer surface of the cardboard and secured thereto by the rubber cement, a photograph being preferably made on white royal 75 smooth bromid paper.

In order to secure the various depths of relief portions of the various layers of board are cut away as shown in Figs. 2 and 3, wherein the near side 14 of the figure will 80 consist of all four layers of cardboard and the far side 15 thereof will consist of only one layer, while the opening 16 will be entirely cut away so as to show the background 10. The near post 17 will consist of four 85 layers while the off post 18 will consist of one layer and so on throughout the entire construction of the relief, wherein the corresponding numerals 19 to 28, as indicated in the drawings in Fig. 1, will correspond 90 with the thickness of the layers shown in Figs. 2 and 3. After cutting away the layers of board and producing the depth of relief has been completed, the drawing and shading or color of the figure is proceeded 95 with in the usual manner. When this process has been completed and the figure appears in its finished form both as to depth and coloring, the entire figure is mounted by means of liquid glue on the velvet back- 100 ground and the velvet background mounted within a frame or a larger background, as the case may be.

The process forming the invention is not restricted to the figure shown in the draw- 110

ings, which serves simply as an example, but may be equally well applied to any other figure and mounted upon any desirable back or mounting other than that mentioned 5 herein.

The invention claimed is:

1. The process of forming depth of relief in a figure for a work of art, consisting of forming a single sheet of a plurality of independent layers of cardboard, securing said 10 layers to each other by means of an adherent medium adaptable for removing from the surface thereof without leaving a residue, producing the figure on the surface of said sheet, and cutting away portions of said layers to produce the natural depth of relief in said figure.
2. The process of forming depth of relief in a figure for work of art, consisting of forming a single sheet of a plurality of independent layers, securing said layers to each 15
- 20

other by means of rubber cement which may be removed from the surface thereof without leaving a residue, producing the figure on the surface of said sheet, and cutting away portions of said layers to produce the natural depth of relief in said figure. 25

3. The process of forming depth of relief in a figure for work of art, consisting of securing a plurality of independent layers 30 of cardboard together so as to form a single sheet therefrom, said layers being secured together by means of an adhering medium adaptable for removing from the surface thereof without leaving a residue, and cutting away portions of said layers around the outlines of said figure so as to produce the natural depth of relief therein. 35

In witness whereof, we have hereunto affixed our signatures.

HERBERT R. HYMAN.
TURNER B. MESSICK.
